UNITED STATES PATENT OFFICE.

RAYMOND H. HAND, OF BRIDGETON, NEW JERSEY, ASSIGNOR OF ONE-HALF TO LAURA L. HAND, OF BRIDGETON, NEW JERSEY.

SPARK-PLUG.

1,232,396.

Specification of Letters Patent. Patented Mar. 2, 1920.

Application filed April 28, 1919. Serial No. 293,151.

To all whom it may concern:

Be it known that I, RAYMOND H. HAND, of Bridgeton, in the county of Cumberland and State of New Jersey, have invented certain new and useful Improvements in Spark-Plugs, and do hereby declare that the following is a full, clear, and exact description thereof.

The object of my invention is the provision of a spark plug for internal combustion engines, which will afford the advantages of exceptional cleanliness, and quick and hot sparks, and thus utilize to the maximum the energy of the gasoline, and so conduct to economy of fuel consumption and increased power therefrom, and to this end my invention consists in a spark plug having the construction substantially as hereinafter specified and claimed.

20 In the annexed drawings:—

Figure 1 is a side elevation, with parts in section of a spark plug embodying my invention;

Fig. 2 is an end view thereof.

25 The spark plug shown is of usual construction in that it comprises a shell or casing 10, threaded to screw into the cylinder and form the ground connection, and a central electrode 11, suitably insulated from the shell and having a binding post 12 for the usual wire connection. The sparking terminal 13 of the central electrode is bent outward toward the rim of the grounded shell 10, so that the current will pass from the tip 30 of said terminal to said shell, and I also provide a ground terminal in the form of a bent finger 14, attached to and projecting from

the shell rim, with its free end close to the angle or elbow of the center electrode where it is bent to form the terminal 13. The current through the central electrode divides so that simultaneously, two independent sparks are produced, one between the tip of the terminal 13 and the shell 10, and the other between the terminal elbow and the finger 14. 40 The finger 14 is preferably of rounded wire, while the terminal 13 is flattened, to form a comparatively wide surface, as I find that by such a form, I get a greater spark than when a round electrode is used. 45

50 The gap between the tip of the terminal 13 and shell is diametrically opposite the place of connection of the ground terminal 14 and the shell.

By simultaneous sparking, ignition takes 55 place instantly at two points, which means more complete combustion of gasoline, with the results of greater cleanliness of spark plugs, and, hence, assurance always of quick and hot sparks, economy of fuel, and 60 greater power and liveliness for the engine.

I claim:—

A spark plug comprising a ground shell, an electrode insulated therefrom, having a terminal bent toward the rim of the shell, 65 and a terminal reaching from the shell toward the elbow of the bent terminal; said bent terminal being flattened from its elbow to its extremity toward the shell and said other terminal being round in cross section. 70

In testimony that I claim the foregoing, I have hereunto set my hand.

RAYMOND H. HAND.
